DESIGN FOR A CABINET FOR A CONTINUOUS COOKER

Walter R. Scharsch, Stockton, Calif., assignor to Cogrisch Products, Inc., Stockton, Calif., a corporation of California

Application May 16, 1941, Serial No. 100,982

Term of patent 14 years

To all whom it may concern:

Be it known that I, Walter R. Scharsch, a citizen of the United States, residing at Stockton, in the county of San Joaquin and State of California, have invented a new, original, and ornamental Design for a Cabinet for a Continuous Cooker, of which the following is a specification, reference being had to the accompanying drawing, forming a part thereof.

In the drawing, Fig. 1 is a perspective view of a cabinet for a continuous cooker looking at the

discharge end and showing my new design, and Fig. 2 is an end elevational view looking at the feed-in end of the cabinet.

The opposite side of the cabinet presents substantially the same appearance as that shown in Fig. 1.

I claim:

The ornamental design for a cabinet for a continuous cooker as shown and described.

WALTER R. SCHARSCH.
